INDIVIDUALLY OPERATED DOOR FOR
HOPPER CARSOrville Ingram, Washington, D. C., assignor to
Unitcast Corporation, Toledo, Ohio, a corpora-
tion of Ohio

Application May 25, 1949, Serial No. 95,362

6 Claims. (Cl. 105—308)

1

My invention relates to railway hopper cars and more particularly to individually operated doors for such cars.

One of the principal objects of the invention is to prevent such a door from sagging on its hinge pins.

Another object of the invention is to provide simple and reliable means for forcing the door to a fully closed position.

Another object is to provide simple and reliable means for freeing the door from engagement with its supporting hook.

A primary feature of the invention consists in having a portion of the reinforcing member which is secured to the outer face of the door project inwardly and engage the housing for the door supporting hooks so as to prevent the door from sagging.

Another feature of the invention consists in providing a door supporting hook with a recess in its outer end for receiving a pry bar to force the door from partially closed to fully closed position.

A further feature of the invention consists in providing the reinforcing member secured to the outer face of the door with a flange extending outwardly therefrom, the flange having upstanding means affording an abutment for a lever to pry a door supporting hook from engagement with the door.

Other and more specific features of the invention, residing in advantageous forms, combinations and relations of parts, will herein-after appear and be pointed out in the claims.

In the drawings,

Figure 1 is a face view of a portion of the door when in fully closed position.

Figure 2 is a sectional view taken on line 2—2 of Figure 1.

Figure 3 is an enlarged view partly in section and partly in elevation of the door supporting hooks.

Figure 4 is a detail sectional view at the inner ends of the hooks.

Figure 5 is a sectional view through the hooks and their housing.

Figure 6 is a sectional view through the outer ends of the hooks.

Figure 7 is a transverse cross sectional view of the hook housing and the associated door showing the hook 12 in engaging position.

Figure 8 is a similar cross sectional view of Figure 7 showing the door in locked position.

In the drawings, 1 represents an individual-

2

along its upper edge (not shown) by hinge brackets 2. The door is of conventional shape having inwardly extending flanges 3 which, when the door is in closed position, are disposed in overlapping relation with a member 4 which extends around three sides of the hopper, the member extending beyond the forward edge of the floor or slope sheet 5 of the hopper to define the opening through which lading discharges from the hopper. Where this member extends beneath the floor sheet of the hopper, it is of angle shape having an outwardly extending flange 6 similar to the member which extends on the sides of the hopper and a downwardly extending flange 7 for connection to an angle member 8 which is rigidly connected to the floor sheet of an adjoining hopper to tie the hoppers together.

Secured to the outer face of the door is a reinforcing member 9 having an outwardly projecting flange 10. The outer face of the reinforcing member affords a surface which is engageable by door supporting hooks 11 and 12 projecting through matched openings in the door and in the reinforcing member. The hook 11 is adapted to support the door in fully closed position, while the hook 12 is adapted to support the door in a partially closed position.

Both hooks are pivotally mounted within a housing 13 which is secured to the floor sheet 5 of the hopper. The top wall of the housing is preferably formed by downwardly diverging portions 14 so that lading within the hopper will be shed onto opposite sides of the housing 35 to discharge from the hopper when the door is open.

Rigid with the reinforcing plate and extending inwardly therefrom through the door itself is a flange 15 which projects into the mouth 40 of the housing 13. This flange may be conveniently formed as a marginal flange of the opening in the reinforcing member and, by having the lower portion thereof project into the mouth of the housing, the door is effectively prevented from sagging on its hinge pins (not shown).

Each hook may be conveniently formed with a laterally extending projection 16 which, when they are moved vertically within the housing 50 13, serve to effectively guide them.

As seen in Figure 6, the outer end of the hook 11 for supporting the door in fully closed position has a portion 17 which extends over and is adapted to overlyingly engage the upper edge of the hook 12 for supporting the door

in partially closed position. It is apparent, therefore, that when the hook 11 is moved downwardly the hook 12 must move correspondingly and it cannot move upwardly until the hook 11 is free from engagement with the door. Hook 11 may be advantageously locked in closed position by a cam or the like 18 which is rotatably mounted on a rivet 19 between an outer face plate 20 and the reinforcing member 9. In view of the manner in which the portion 17 overlaps the hook 12, it will, of course, be appreciated that so long as the cam is in engagement with the portion 17 of hook 11 both hooks are prevented from moving upwardly.

At their inner ends, the hooks may be conveniently mounted upon a sleeve 21 which is supported by a rivet 22. While the rivet 22 may be sufficient to support the pivoted ends of the hooks, each of them may be advantageously provided with a lug or the like 23, the outer surface of which is concentric with the pivotal axis of the hook and is adapted to engage the floor sheet 5. In this manner, the rivet and sleeve 21 are relieved from all strains incident to supporting the pivoted ends of the hooks. It will, of course, be appreciated that the hooks are pivotally associated with the housing 13 before the housing is secured to the floor sheet 5. The outer end of hook 12 is formed with a recess 24 for receiving a pry bar. The inner wall of the recess adjacent the outermost end of the hook is preferably inclined, as indicated at 25, so that a pry bar may be readily inserted therein.

Extending outwardly from the face plate 20 is a lug or the like 26 which affords an abutment for the pry bar so that, when force is applied to the pry bar and one end thereof is in the recess 24, the door is forced from partially closed to fully closed position to thereby enable hook 11 to support the door.

A pry bar may also be used to move the hooks into inoperative positions. For this purpose, the hooked end of hook 12 for supporting the door in partially closed position is formed with a recess 27 to receive an end of the pry bar. The reinforcing member 9 is also provided with a lug or projection 28 which extends upwardly from the outwardly projecting flange 10 and affords an abutment for a pry bar when it is used to move the hooks into inoperative positions. Even though an unlocking force is only exerted on hook 12, upward movement by it will be transmitted to hook 11 through the portion 17 of the hook 11 which overlappingly engages the upper portion of hook 12. A pry bar *a* is shown in Figure 1 in the position it occupies when it first engages hook 12 and the same pry bar is shown in a substantially horizontal position after the door has been freed from the hooks and the latter are supported in an elevated inoperative position.

A pry bar designated *b* is shown in Figure 3 for forcing the door to fully closed position. When the pry bar is first inserted in the recess 24 in the hook 12, it will probably occupy a somewhat inclined position as shown in Figure 3 but, after being once inserted, the trainman, upon applying a force to the outer end of the pry lever, will move it from its inclined position into a position where it engages the lug 26 so that the door may be then forced to fully closed position.

It is obvious that various changes may be made in the embodiment of the invention il-

lustrated without departing from the scope of the appended claims.

What I claim is:

1. An individually operated door for a rail-way hopper car comprising a pair of pivotally mounted hooks for respectively supporting the door in partially closed and fully closed positions, a housing secured to the floor of the hopper in which said hooks are pivotally mounted, and a plate-like member secured to the outer face of the door having an opening through which said hooks project, said member having a portion projecting inwardly adjacent said opening and engaging said housing when the door is closed for partially supporting the door thereon.

2. An individually operated door for a rail-way hopper car comprising a pivoted door having an opening therethrough and provided with a plate-like reinforcing member on its outer face, a pair of pivotally mounted hooks for respectively supporting the door in partially closed and in fully closed positions, a housing secured to the floor of the hopper in which said hooks are pivotally movable, an opening in said plate member matching the opening in the door through which said hooks project, and a flange surrounding the opening in said plate member projecting inwardly into engagement with the inner walls of said housing.

3. An individually operated door for a rail-way hopper car comprising a pivoted door having an opening therethrough, a plate-like reinforcing member secured to the outer face of the door and having an opening therein matching the opening in the door, a pair of pivotally mounted hooks extending through said openings respectively having ledges engageable with the outer face of said member for supporting the door in partially closed and in fully closed positions, a housing secured to the floor of the hopper in which said hooks are pivotally mounted, and an inwardly extending marginal flange surrounding the opening in said plate member and projecting through the opening in said door into engagement with the inner walls of said housing.

4. An individually operated door for a rail-way hopper car comprising a pivoted door having an opening therethrough and provided with a plate-like reinforcing member on the outer face of the door, a pair of pivotally mounted hooks extending through said opening and respectively supporting the door in partially closed and in fully closed positions, a housing secured to the floor of the hopper in which said hooks are pivotally movable, said hooks projecting through the body of the door, one of said hooks being formed adjacent its outer end with a recess for receiving a pry bar so that the door may be pried from partially closed to fully closed position and means on said member projecting through the opening in said door into engagement with a portion of said hopper when the door is in fully closed position for partially supporting the door thereon.

5. An individually operated door for a rail-way hopper car comprising a pivoted door having an opening therein, a plate-like reinforcing member secured to the outer face of the door and having an opening therein matching the opening in the door, a pair of pivotally mounted hooks extending through said openings for respectively supporting the door in partially closed and in fully closed positions, a housing

secured to the floor of the hopper, said hooks projecting through the body of the door in which said hooks are pivotally movable, the hook for supporting the door in partially closed position having a recess in its outer end for receiving a pry bar, and means projecting outwardly from the door affording an abutment for the pry bar when it is inserted in said recess to force the door from partially closed to fully closed position.

6. An individually operated door for a railway hopper car comprising a pivoted door, a pair of pivotally mounted hooks for respectively supporting the door in partially closed and in fully closed positions, a reinforcing member secured to the outer face of the door and having an opening therein matching with an opening

5 in the body of the door through which said hooks project, said reinforcing member having an outwardly projecting flange, means rigid with said flange affording an abutment for a lever to act on one of the hooks, and means for causing said one hook on action thereon of said lever to move said other hook and temporarily elevate both hooks out of the way of said door.

ORVILLE INGRAM.
